[57] CLAIM

The ornamental design for a support stand for a hanging
seat or similar article, substantially as shown and de-
scribed.

DESCRIPTION

FIG. 1 is a perspective view of a support stand for a
hanging seat or similar article showing my design;
FIG. 2 is a side elevational view thereof;
FIG. 3 is a top plan view thereof;
FIG. 4 is a rear elevational view thereof;
FIG. 5 is a front elevational view thereof.The design is characterized by the specific configura-
tion of the arcuate handle support in combination with
the particular arrangement of the splayed leg extensions
as best illustrated in FIGS. 1 and 2.*FIG. 1*

FIG. 2

FIG. 3

FIG. 4
